UNITED STATES PATENT OFFICE.

RALPH M. SHARAF, OF NEW YORK, N. Y., ASSIGNOR TO R. M. SHARAF MACHINE CO.,
OF BOSTON, MASSACHUSETTS, A CORPORATION OF MASSACHUSETTS.

ZIGZAG MECHANISM FOR SEWING MACHINES.

Application filed April 2, 1917, Serial No. 159,053. Renewed July 13, 1921. Serial No. 484,509.

To all whom it may concern:

Be it known that I, RALPH M. SHARAF, a citizen of the United States, and a resident of the borough of the Bronx, in the city and 5 State of New York, have invented certain new and useful Improvements in Zigzag Mechanism for Sewing Machines, of which the following is a specification.

The present invention relates to zig-zag 10 mechanism for sewing machines, and more particularly sewing machines of the two needle type. It is an object of the present invention to provide an improved zig-zag mechanism operable primarily by spiral 15 gears, and with which the hooks or loopers will be accurately and synchronously operated in connection with the zig zagging of the needles.

With these and other objects in view, an 20 embodiment of my invention is shown in the accompanying drawings, and this embodiment will be more fully described hereinafter with reference thereto, and the invention will be finally pointed out in the 25 claims.

In the accompanying drawings;

Figure 1 is a top view with parts broken away, also showing the means for zig-zagging the needles;

Figure 2 is a side view of the same;

Figure 3 is a front end view thereof;

Figure 4 is a side view partly in elevation and partly in section of the loopers;

Figure 5 is a top view partly in elevation 35 and partly in section of the loopers, taken along the line $\alpha-\alpha$ of Figure 4, and

Figure 6 is a view of the inner side of one of the loopers.

Similar reference characters indicate corresponding parts throughout the several 40 figures of the drawings.

Referring to the drawings, the sewing machine head, which is of the usual type, is shown partly in dotted lines and is provided with a drive shaft 10 extending therethrough, and having two spiral gears 11 and 12 thereon, the gear 11 engaging a laterally disposed gear 13 supported upon a suitable bracket within the head, and having a ratio 45 to the gear 11 of 1 to 2, while the gear 12 50 engages a laterally disposed gear 14, upon

the upper end of an upright shaft 15, and having a ratio to the gear 12 of 1 to 1. A cam 16 is carried by the shaft of the gear 13, and a rod 17 having a slot 18, slidably 55 engages the said shaft and is provided with rollers 19 and 20 which engage the cam at either side thereof, the rotation of the cam, thereby causing the said rod 17 to reciprocate.

The forward end of the rod 17 is pivotally connected to a lever 21, mounted upon a supporting bracket 22, and pivotal about the pin 23. The arm of the lever 21 is provided with an arcuate slot 24 in which is secured 60 pivotally by a nut 25 the inner end of a rod 26, the outer end of which is pivotally connected by a screw 27 between lugs 28 and 65 29 of the swinging frame 30. The frame 30 is hingedly supported between bearings 31 and 32, and is curved outwardly as shown in Figure 1 to embrace the presser foot bar 33 indicated in dotted lines. Upper and lower bearings 34 and 35 are provided on the frame 30, in which is reciprocatingly mounted the needle bar 36 provided at its end with the two needles 37 and 38, and adapted to be reciprocated by the arm 39, pivotally connected to the clamp 40 of the needle bar at one end, and to the rotating drum 41 at the other end, the said drum 41 being carried at the end of the shaft 10. It will be seen that as the needle bar descends twice, the frame 30 is moved outwardly and inwardly once. By loosening the nut 25 and changing the position thereof in the slot 24, the throw 70 of the rod 26 may be changed and the amount of the zig-zag regulated. As the slot extends over the pivot point 23, the nut 75 may be brought directly over the same so that there will be no movement of the frame 30, and hence no zig-zag action.

Beneath the base plate of the machine, a counter-shaft 50 is mounted at one end in the bearing support 51, and is operated from the drive shaft 10 by a spiral gear 52 at the lower end of the vertical shaft 15, meshing 80 with a spiral gear 53 on the said shaft 50, causing the same to move equally with the driving shaft.

A looper driving shaft 54 is mounted between the bearing support 51 and the

bearing support 55 at the forward end of the base plate, this shaft being turned by gears 56 and 57 respectively on the shaft 50, and on the shaft 54, and having a ratio of 1 to 2 so that the shaft 54 is rotated twice to one revolution of the shaft 50. The loopers A and B are operated by mitre gears 58 and 59 on the said shaft 54, and as the operation of each is identical, I will only describe in detail the looper B, the looper A being operated through mitre gears 58—81.

A cam shaft 60 is mounted between the bearing supports 51 and 55, and is operated from the shaft 54 by means of a pawl 61 on the shaft 54 engaging an intermittent sprocket 62 secured rigidly to the shaft 60, the latter being thus rotated intermittently by the action of the shaft 54 and its pawl 61, and turning through an angle of 90° for each complete revolution of the shaft 54.

The supporting boxes 63 of the loopers are adjustably supported beneath the looper opening 64 of the base plate, the side flanges 65 and 66 of said boxes being provided with slots 67 and 68 through which extend stationary bolts 69 and 70, upon which sleeves 71 and 72 are held by a plate 73 and nuts 74. By loosening the said nuts 74, it will be seen that the connection between the sleeves 71 and 72 and the boxes 63 is loosened, and their position may be adjusted in the slots 67 and 68.

The looper box 63 is provided with an opening 75 therethrough, in which is pivotally mounted upon stub shafts 76, the bearing block 77 of the looper 78, the shaft 79 of the looper extending through the bore 80 of the block and being provided at its lower end with a mitre gear 81 which engages the mitre gear 59 of the shaft 54. The horizontal axis of the stub shaft 76 intersects the axis of the looper shaft 79.

The upper end of the looper box 63 is recessed as at 82, and the block 77 is spaced from the rear of the recess 75 as at 83 (Fig. 5) to permit of the oscillation of the loopers, as hereinafter described. At one side of the looper box there is provided a slot 84 which extends upwardly into the flange 65, and a slide piece 85 is mounted therein, being held from displacement at the upper end by the closed portion of the slot extending into the flange, and at the lower end by a closure member 86 secured to the looper box by screws 87, the said member 86 being provided with a bore 88 extending therethrough, in which is slidably mounted a rod 89, the upper end of which extends through a similar opening 90 in the flange 65, and is adapted to be reciprocated therein. The slide piece 85 is clamped to and movable with the rod 89 by means of an extension 91 embracing and secured to the said rod by means of a screw 92. A diagonally disposed slot 93 is provided in the slide piece

85, which is engaged by a pin 94, secured in the block 77 by a screw 95 and extending through a transversely disposed slot 96 in the box 63.

The rod 89 is provided at its lower end 70 with a yoke 97 which embraces the eccentric or cam 98, carried by the cam shaft 60. Thus it will be seen that as the cam shaft is intermittently rotated, the rod 89 is raised intermittently during two periods, and lowered intermittently during two periods, this cycle occurring during four revolutions of the looper. By this operation the loopers are moved inwardly and outwardly by means of the pin 94 acting on the inclined 80 slot 93 of the slide piece 85, stopping intermediate during the inward and outward movement. During this cycle the needles go up and down twice, once in each extreme position of their zig-zag movement, or once 85 for two revolutions of the loopers. In the vertical or intermediate position the loopers rotate without being in operative relation to the needles. When the loopers pivot over into one of the other positions corresponding to the position of the needles, the latter are in operative relation to the hooks of the loopers. The loopers, it will be seen, rotate continuously while they are pivotally moved or tilted intermittently on the 95 stub shafts 76, located above the mitre gears 81.

The use of spiral gears for the driving of the zig-zagging mechanism results in a positive and noiseless operation of the machine. 100 Also such gears require less space for obtaining the different ratios of movement of the shafts.

With my improvements the zig-zagging operation of the loopers synchronously with the needles, is at the same time simple in operation and maintenance, and absolutely accurate.

I have illustrated and described a preferred and satisfactory embodiment of my invention, but it is obvious that changes may be made therein within the spirit and scope thereof as defined in the appended claims.

I claim:

1. A zig-zag mechanism for sewing machines, comprising a needle bar, two needles connected with said bar rigidly and located out of line with respect to the direction of feed, means for reciprocating the needle bar and for imparting a lateral movement thereto, loopers arranged to cooperate with said needles, and means for shifting said loopers laterally in correspondence to the lateral movements of the needles, the central axes of said loopers being movable during said shifting movement along a vertical plane intersecting both of said axes.

2. A zig-zag mechanism for sewing machines, comprising a needle bar, two needles connected with said bar rigidly and located

in transverse alignment with respect to the direction of feed, means for reciprocating the needle bar and for imparting a lateral movement thereto, loopers arranged to co-
5 operate with said needles, and means for shifting the said loopers laterally in correspondence to the lateral movements of the needles, the central axes of said loopers being movable during said shifting movement
10 along a vertical plane intersecting both of said axes.

3. A zig-zag mechanism for sewing machines, comprising a needle, means for imparting thereto a longitudinal reciprocation and a lateral movement, a looper cooperating with said needle, a support in which said looper is journaled, pivotal means on which said support is mounted to rock about an axis intersecting the axis about which
15 the looper turns, and means for rocking said support to shift the looper laterally in correspondence to the lateral movements of the needle.

4. A zig-zag mechanism for sewing machines, comprising a needle, means for imparting thereto a longitudinal reciprocation and a lateral movement, a looper cooperating with said needle and mounted to turn about an axis extending lengthwise with reference to the needle, a support in which said looper is journaled and which is mounted to swing about an axis intersecting the one about which the looper turns, and means for rocking said support to shift the looper laterally in correspondence to the lateral movements of the needle.

5. A zig-zag mechanism for sewing machines, comprising a needle, means for imparting thereto a vertical reciprocation and a lateral movement, a looper cooperating with said needle, an upright shaft to the upper portion of which said looper is secured, looper-driving mechanism connected with the lower portion of said shaft, a support in which said shaft is journaled, mounted to swing about a horizontal axis located below the looper but above the driving connection at the lower portion of said shaft, and means for rocking said support to shift the looper laterally in correspondence to the lateral movements of the needle.

6. A zigzag mechanism for sewing machines, comprising a needle, means for imparting zigzag movement to the needle, means for reciprocating the needle, a looper for cooperation with said needle, means for rotating the said looper twice for each up and down movement of the needle, pivoted means for supporting said looper, a cam shaft, reciprocating means engaging the said cam shaft and adapted to have to and fro movement, means on said reciprocating means engaging said pivoted means and adapted to move the same about the pivots thereof during the to and fro movement of

said reciprocating means to move the said looper synchronously with the zigzag movement of the needle, the axis of rotation of the looper moving in a vertical plane.

7. A zig-zag mechanism for sewing machines, comprising a needle, means for imparting zig-zag movement to the needle, means for reciprocating the needle, a looper, pivoted means supporting said looper, a reciprocating member, means for intermittently reciprocating said reciprocating member vertically, and means inclined to the direction of movement of said reciprocating member and actuated by the movement of said reciprocating member and adapted to pivotally move the said supporting means of the looper.

8. A zigzag mechanism for sewing machines comprising a needle, means for imparting zigzag movement to said needle, means for reciprocating said needle, a looper, means for rotating the said looper twice for each up and down movement of the needle, and means for intermittently moving said looper to and fro to correspond to the movement of said needle and stopping the said movement at the ends of the to and fro movement and intermittently at an intermediate stage of both said to and said fro movement.

9. A zig-zag mechanism for sewing machines, comprising a needle, means for imparting thereto a longitudinal reciprocation and a lateral movement transversely to the line of feed of the work, a looper cooperating with said needle, a pivoted support in which said looper is journaled, a reciprocating member, and means on said reciprocating member to engage the pivoted support and rock the same on its pivot transversely to the line of feed of the work to move the looper in correspondence to the lateral movement of the needle, the central axis of said looper being movable in a vertical plane during said rocking movement.

10. A zig-zag mechanism for sewing machines, comprising a needle, means for imparting thereto a longitudinal reciprocation and a lateral movement transversely to the line of feed of the work, a looper cooperating with said needle, a pivoted support in which said looper is journaled, a reciprocating member, and cooperating portions on said support and on said member, having an effective line of action disposed obliquely to the path of said member, to rock said support on its pivot transversely to the line of feed of the work and move the looper in correspondence to the lateral movement of the needle, the central axis of said looper being movable in a vertical plane during said rocking movement.

11. In a zig-zag mechanism for sewing machines, the combination of a drive shaft, a counter shaft, a cam shaft, a gear connection

between the cam shaft and the drive shaft, as my invention, I have signed my name in
needle oscillating means connected to the cam shaft, a looper horizontally pivoted,
and a mechanism connected to the counter-
5 shaft for operating the same and oscillat-
ing it upon its pivot.

In testimony, that I claim the foregoing

Witnesses:
